JOHN OLSEN, OF MILWAUKEE, WISCONSIN, ASSIGNOR OF ONE-HALF TO WILLIAM L. GREENLEAF AND ONE-HALF TO JOHN M. BEECH, OF MILWAUKEE, WISCONSIN.

Improvement in Sieve-Cleaners, or

SIEVE-CLEANER.

No. 874,080. **Specification of Letters Patent.** Patented Dec. 17, 1907.

Application filed May 6, 1907. Serial No. 372,176.

To all whom it may concern:

Be it known that I, JOHN OLSEN, a citizen of the United States, residing at Milwaukee, in the county of Milwaukee and State of Wisconsin, have invented certain new and useful Improvements in Sieve-Cleaners, of which the following is a specification, reference being had to the accompanying drawing, forming a part thereof.

This invention relates more particularly to brushes for cleaning gyratory or shaking sieves having cloth tops and woven wire bottoms between which the brushes are confined by the sieve frames in an inverted position or with the bristles or wipers presented upwardly to the underside of the cloth.

The main objects of the present invention are simplicity, lightness and durability of construction, greater activity and efficiency in operation, to prevent or materially reduce wear on the sieve frames, and to avoid the necessity of providing them with linings to protect them against the action of the brushes, to prevent the brushes from becoming stuck and inactive by reason of sagging cloth, to prevent crystallization and consequent weakening and breaking of the brush frames, and generally to improve the construction and operation of sieve cloth cleaners of this class.

It consists in certain novel features of construction and in the peculiar arrangement and combinations of parts as hereinafter particularly described and pointed out in the claims.

In the accompanying drawing showing on an enlarged scale a sieve cleaning brush embodying the invention, like letters designate the same parts in the several figures.

Figure 1 is a plan view of the brush; Fig. 2 is a side elevation of the same as viewed from the lower side with reference to Fig. 1; and Fig. 3 is a cross section on the line 3-3, Fig. 1.

Sieve brushes of this class as usually made, have solid or disk shaped backs or continuous annular frames, generally made of or reinforced by sheet metal and provided on the under side with bearings usually formed by downwardly pressed bulges in the sheet metal. Such brushes are usually quite heavy, and being comparatively inelastic, strike the sieve frames with such force as to necessitate lining them to avoid rapid wear

and destruction not only of the sieve frames, but of the brushes themselves. Being comparatively heavy and inelastic, the metal of which the brush frames are made or with which they are backed, soon becomes crystallized and brittle with the constant and violent striking of the brushes against the sieve frames, so that from this cause brushes are frequently broken. When the bearings on the under side of the brushes are formed as above stated, by depressions in the sheet metal frames or backs, their constant movement over the woven wire supports or screens on which they rest, soon wears through the thickness of the sheet metal, removing the bearings and materially reducing if not destroying the efficiency of the brushes, and if such bearings are formed by the lugs which hold the bristles or wipers, the wearing away of the thickness of the sheet metal releases the bristles or wipers and renders the brushes inoperative.

The construction of the brush or cleaner as herein shown and described, is designed to avoid the objections and difficulties above mentioned.

Referring to the drawing, the cleaner or brush consists of an open resilient frame *a*, and of flexible tufts or wipers *b* of bristles or other suitable material secured thereto by inwardly and upwardly bent lugs *c*. The frame *a* consists of a resilient band of metal or other elastic material preferably bent into approximately circular or annular shape as shown, a gap or space being left between the free ends of the band to permit contraction or compression and recoil of the brush frame when it strikes the sieve frame. One end of the band is bent transversely inward and forms an abutment or stop *d*, as shown in Fig. 1, for the other end of the band to strike against, in order to prevent contraction or compression of the brush frame to such a degree as would destroy or reduce its resiliency or bend it beyond its capacity to resume its original form. The band is curved or extended downwardly at intervals along its lower edge to form bearings *e*, as shown in Figs. 2 and 3, to come in contact with the woven wire sieve bottom or brush support, and to give the tufts or wipers an oscillatory or rocking movement against the sieve cloth as said bearings ride over the elevations and depressions in said woven wire support. Between the bearings *e* the narrower parts

of the band are formed with inwardly and upwardly bent lugs *c* for holding the tufts or wipers. The lower parts of these lugs where they join the lower edge of the band being thus elevated out of contact with the woven wire brush support or screen of the sieve frame, are prevented from being worn away and releasing the tufts or wipers, the edge-wise disposition of said bearings with relation to said support or screen affording ample material for wear before the lugs can come in contact with and be subjected to abrasion by said support or screen. The life of the brush is thus materially prolonged and its efficiency increased.

The bristles, fibers or other material of which the tufts or wipers are composed, are preferably folded into and held by light sheet metal strips *f* in continuous or long bands, and these bands are cut into sections or wipers of the desired lengths, which are clasped to the inner side of the frame *a* by the lugs *c*, as shown in Fig. 3, the free ends or edges of the tufts or wipers projecting upwardly some distance above the frame so as to reach and effectively clean the entire area of cloth within the sieve frame.

The brush is preferably provided with two of these tufts or wipers, arranged substantially as shown in Fig. 1, so that with sagging cloth the brush will tend to swing around one of them as a pivot, and thus work itself free, avoiding the objection to brushes having continuous rings of bristles or the like or three or more symmetrically arranged tufts or wipers into or between which sagging cloth tends to settle and thus prevent the free movement of the brushes so made.

46 The brush constructed as herein shown and described being very light and elastic, recoils quickly when it strikes the sieve frame and is more active and efficient in operation, covering more area in a given time than the heavier and comparatively inelastic brushes or cleaners in general use.

In case the tufts or wipers are cut or worn off or are otherwise injured and become defective before the brush frame is worn out, they can be readily renewed by bending the lugs *c* slightly inward, removing the tufts or wipers thus released, and replacing them with new ones.

I claim:

1. A sieve cleaner having an elastic frame 55 open on one side and provided with a wiper projecting upwardly therefrom, substantially as described.

2. A sieve cleaner comprising a curved elastic frame open on one side and provided 60 with a number of separate upwardly projecting wipers, substantially as described.

3. A sieve cleaner comprising a frame consisting of a curved elastic metal band open on one side and having inwardly and upwardly bent lugs and wipers clasped between said band and lugs and projecting upwardly 65 therefrom, substantially as described.

4. A sieve cleaner comprising a resilient frame consisting of a curved metal band 70 open on one side and formed at intervals along its lower edge with downwardly extending bearings and between said bearings with inwardly and upwardly bent lugs, and wipers clasped between said band and lugs 75 and projecting upwardly therefrom, substantially as described.

5. A sieve cleaner comprising a resilient frame consisting of an open elastic metal band bent into approximately annular shape, 80 one of its free ends being bent inwardly and forming a transverse striking abutment opposite the other end, and a wiper secured to said band and projecting upwardly therefrom, substantially as described.

6. A sieve cleaner comprising an elastic annular metal band severed on one side and formed at intervals along its lower edge with downwardly extending bearings and between said bearings with inwardly and upwardly 90 bent lugs and wipers clasped between said lugs and band and projecting upwardly therefrom, substantially as described.

7. In a sieve cleaner the combination of an open curved elastic metal frame formed at intervals with inwardly and upwardly bent lugs and fibrous material folded into a confining strip, clasped therewith between said lugs and frame and projecting upwardly 95 therefrom, substantially as described.

In witness whereof I hereto affix my signature in presence of two witnesses.

JOHN OLSEN.
